UNITED STATES PATENT OFFICE.

RANSOM R. SPOORE, OF CLIFTON SPRINGS, NEW YORK.

FENCE-POST.

SPECIFICATION forming part of Letters Patent No. 469,322, dated February 23, 1892.

Application filed February 26, 1891. Serial No. 382,901. (No model.)

To all whom it may concern:

Be it known that I, RANSOM R. SPOORE, of Clifton Springs, in the county of Ontario and State of New York, have invented certain new and useful Improvements in Fence-Posts; and I do hereby declare the following to be a full, clear, and exact description of the invention, such as will enable others skilled in the art to which it appertains to make and use the same.

10 My invention relates to an improvement in fence-posts, and more particularly to such as are made of metal, the object being to produce a fence-post which shall be substantial in construction and to which the fence wires or rails may be easily, quickly, and effectually attached.

15 A further object is to construct a metallic fence-post in such manner that the fence wires or rails may be securely attached thereto by means of ordinary nails and said wires or rails, as well as their fastening devices, shall be prevented from lateral or other displacement.

20 A further object is to provide a metallic fence-post with improved means for securing the post in the ground.

25 A further object is to produce a fence-post which shall be simple in construction, yet substantial, and which shall be cheap to manufacture and set up for use.

30 With these objects in view the invention consists in the combination, with a fence-post, of flanges or plates projecting from said post and spaced apart, and nails or pins projecting through said post between the flanges or plates and adapted to secure the fence wires or rails firmly to the post.

35 The invention also consists in certain novel features of construction and combinations and arrangement of parts, as hereinafter set forth, and pointed out in the claims.

40 In the accompanying drawings, Figure 1 is a view in perspective of my improved fence-post, showing the manner of setting the same up and attaching the wires or rails thereto.

45 Fig. 2 is a vertical sectional view. Fig. 3 is a view illustrating the blank from which the post is made before it is rolled into proper shape. Fig. 4 is a view which illustrates the 50 device after it has been rolled into proper shape. Figs. 5, 6, 7, and 8 are views of modifications.

My improved fence-post is made, preferably, of wrought iron or steel and is first rolled or otherwise formed in the shape illustrated in Fig. 3—that is to say, in the form of a cross in cross-section, having leaves or members 1 2 3 4. The blank thus produced is passed between suitable rolls and the leaves or members 1 2 bent and made to produce 60 two parallel flanges or plates *a a*, as shown in Figs. 1 and 4. The partially-completed post is again passed through suitable rolls and the arms or members 3 4 bent out and made to align with each other to produce the body 65 of the post, as shown in Figs. 1 and 4. The lower end of the body portion *c* of the post is bent to produce a flange *d*, whereby the post may be securely embedded in the ground. To further insure the rigidity of the post in 70 the ground, the lower ends of the plates or members *a a* are bent laterally at right angles to produce flanges *d' d'*, which preferably project beyond the longitudinal edges of the post.

75 To prevent lateral displacement of the post, it is desirable to provide supports adapted to rest upon the surface of the ground, and for this purpose the flanges or plates *a a* are cut at points near their lower ends and bent upwardly to produce flanges or supports *e*, said flanges or supports being adapted to rest upon the surface of the ground or slightly beneath the same, as shown in Fig. 1, and thus prevent lateral or swaying movement 80 of the post. The post at the end of a line of fence (for instance, a corner-post) is preferably provided with an additional brace *f* to withstand the strain brought to bear on said post by stretching the wires in the construction of the fence. This brace *f* may be a rod or bar having a bifurcated upper end *e'*, adapted to embrace the body portion *c* and be secured thereto by a suitable pin *e''*. The lower end of the brace *f* is adapted to be embedded in the ground, as shown in Fig. 1, and made to bear against a stone, or, if desired, a stake may be substituted for the stone.

85 The body portion *c* of the post is provided with a series perforations *g* between the 100 plates or flanges *a a* for the reception of a series of wrought nails *h*, of ordinary form. These nails *h* are adapted to pass between said plates or flanges, extend beyond their

free edges, and neatly fit in the space between said plates or flanges.

In constructing a fence a wire is placed on the protruding end of the nail, as illustrated 5 at the central portion of Fig. 1, and then, by means of a claw-hammer or other suitable implement, the nail is bent up and made to embrace the wire, as clearly shown in Fig. 2, the wire being thus securely held and made 10 to bear on the free edges of the plates or flanges *a a*. By this construction it will be readily seen that the wires will be made to have a broad substantial bearing against the post, that they will be securely held thereto by 15 the nails *h*, and that said nails will be held from lateral or other displacement, being snugly held between the plates or flanges *a a*.

With this class of fences it is customary to 20 secure a wooden rail at the top, and for the purpose of supporting this rail I provide a metallic plate *i*, adapted to be secured to the post by means of one of the nails *h*, or, if desired, said plate may be secured to the post by means of a rivet or otherwise. The edge 25 of the plate *i* is bent at right angles and provided with teeth *i'*, adapted to enter the wooden rail and securely hold the same.

If desired, the flanges or supports *e* may be 30 made to project from the post at a point slightly beneath the surface of the ground and an additional brace *j* provided. This brace will preferably be made in the form shown most clearly in Fig. 2, having an arm *k* and an arm *k'*. The upper end of the arm 35 *k* is provided with a hook *k²*, adapted to pass through a perforation *k³* in the post. The arm *k'* of the brace *j* is adapted to pass through a perforation in the lower portion of the post and rest upon the surface of the 40 ground, the free end of said arm being preferably twisted to lie flat on the ground.

Instead of producing the post as above set forth it may be made as shown in Fig. 5—that is to say, a piece of metal may be first 45 bent into the form of a rectangular box open at top and bottom and one edge, and then have its free edges bent out to produce flanges *m*.

In this form of the invention the fastening 50 devices will be made to pass between the parallel portions of the post and secure the wire to the post, so that it will lie flat against the flanges *m*, thus having a very broad and substantial bearing. The lower ends of the flanges *m* will be bent out to produce flanges 55 *m'*, and the lower ends of the body portion may be bent out to produce flanges *m²*.

In the form of the invention shown in Fig. 6 one flange or plate *a* is made integral with the body portion *c* and the other made separate 60 therefrom, the two being held together by means of bolts *n* and spaced apart at the proper distance by means of spacing blocks or collars *n'*.

In the form of the invention shown in Fig. 65 7 the body portion *c* and flanges or plates *a* are made of separate pieces of metal and riveted or otherwise secured together.

In the form of the invention shown in Fig. 8 the post is composed of two angle-irons secured together by suitable bolts or rivets and 70 spaced apart by blocks *o*, said blocks being spaced apart from each other sufficiently to permit the passage of the securing-nails which support the fence-wires.

It is evident that other slight changes 75 might be made in the details of construction of my invention without departing from the spirit thereof or limiting its scope. Hence I do not wish to limit myself to the precise details of construction herein described; but, 80

Having fully described my invention, what I claim as new, and desire to secure by Letters Patent, is—

1. The combination, with a fence-post, of flanges or plates projecting therefrom and 85 spaced apart, and nails or pins projecting through said post between the flanges or plates, their sides engaging said flanges and adapted to secure the fence wires or rails firmly to the post, substantially as set forth. 90

2. In a fence-post, the combination, with a flat portion, flanges slightly separated and extending approximately parallel with each other and at right angles to the flat portion, and nails or pins projecting through said 95 post between the flanges or plates, their sides engaging the inner walls of said flanges and adapted to secure the fence wires or rails firmly to the post, of base-flanges extending laterally from the flat plate and the parallel 100 flanges, substantially as set forth.

3. In a fence-post, the combination, with a body portion bent outwardly at its lower end to produce a flange, of parallel plates projecting from said body portion, flanges at the 105 lower ends of said parallel plates, and flanges bent up from said plates and adapted to lie parallel with the first-mentioned flanges, substantially as set forth.

4. In a fence-post, the combination, with a 110 body portion having perforations therein, of a brace having one arm hook-shaped at its end to enter one of said perforations in the post and the other arm being adapted to pass through a perforation in the post and rest 115 upon the ground on opposite sides of the post, said last-mentioned arm being twisted.

5. In a fence-post, the combination, with a body portion, of two parallel plates projecting from one face thereof, a fastening device 120 passed through said body portion and between the parallel plates, and a plate secured to the post by said fastening device, said plate being provided with teeth adapted to enter a rail and thus secure said rail to 125 the post.

In testimony whereof I have signed this specification in the presence of two subscribing witnesses.

RANSOM R. SPOORE.
